UNITED STATES PATENT OFFICE.

LOUIS S. DEITZ, JR., OF RIFLE, COLORADO.

PROCESS AND APPARATUS FOR SCREENING MATERIALS.

Application filed September 29, 1926. Serial No. 138,520.

The present invention relates to a process and apparatus for screening or classifying materials and the object is to provide a process for this purpose and an apparatus of this character which will effectively screen out evenly, with substantial completeness and expedition, the finer grades—that is to say—the smaller sized particles of comminuted substances.

10 In the accompanying drawings:—

Figure 1 is a diagrammatic view in plan of one embodiment of the apparatus,

Figure 2 is a plan view of a different form of construction,

15 Figure 3 is a sectional view on the line 3—3 of Figure 2.

Figure 4 is a plan view of another embodiment of the invention in which a rotary screen is employed.

20 Figure 5 is a detail view on a magnified scale indicating the operation that takes place.

In the present process the solids made up of relatively large and small particles are mixed with water or other liquid and are held in 25 suspension therein. This liquid is then caused to flow in a slow moving stream. Extending through and across the stream is a screen. This screen is caused to have a movement transversely to the direction of movement 30 of the stream and at a speed decidedly in excess of the speed of the stream. It has been found that for each condition there is a definite ratio of speed of screen to speed of solution, above which the screen will operate and 35 below which it will instantly clog.

It has been found that with such a combination and action, a relatively coarse screen can be employed and yet only particles of much less area than the area of the screen 40 openings will pass through the screen, while particles of approximately the size of the screen openings and indeed those materially less than the same will not pass through the screen but will be held back and will either 45 drop to the bottom whereby they may be extracted or can be otherwise disposed of.

By this operation, greater screening rates and denser pulps can be used while a high-grade classification is secured.

50 The apparatus for carrying out the process may be embodied in various forms. Thus referring to Figure 1, a tank or container 6 is employed having a relatively large body and an intake feed portion 7 of less cross sectional

area than the body 6. The outlet end is indicated generally at 8 and may lead to any suitable receiver. The liquid that constitutes the vehicle for the materials to be separated or classified and carrying such materials in suspension, is delivered from any suitable source to the feed inlet 7 and flows in the direction of arrows into the body 6 where it spreads out into a large mass that has a slow movement through said body to the outlet end 8. In the body and extending through and across the stream is a screen indicated at 9. This screen is movable edgewise and is operated by any suitable means through and across the stream of material. For example, it may be vibrated either horizontally or vertically. Its movement, except when it comes to rest at the ends of its stroke, is at a greater rate of speed than the movement of the material bearing liquid. It has been found that by reason of this relatively rapid movement 75 of the screen only fine particles much less in area than the area of the screen openings are allowed to pass, while the larger particles, even of considerably less size than the screen openings and those approximately the same 80 size will not pass through the screen but will be baffled back. It has been found, moreover, that with such a structure the screen is not apt to become clogged.

A practical embodiment of the invention is 85 illustrated in Figures 2 and 3. In this form of structure a cylindrical casing or container 10 is employed having a feed trough 11 surrounding its upper portion with ports 12 opening from the trough to the interior of the 90 container at various points. An outlet for the fine material is shown in the form of a vertical centrally disposed pipe 13 having a coupling 14 at its lower end that connects with an outlet pipe 15. The pipe 13 is provided 95 with inlet ports 16. The bottom of the container 10 may have an outlet 17 for the residues. The outlets 15 and 17 may be provided with suitable controlling valves 18 and 19. Mounted on the vertical pipe 13 and surrounding the portion of the same having the inlet ports 16 is a tubular screen 20 through which the liquid entering the container, must pass in order to gain access to the ports 16 and thus to the interior of the pipe 13. The 100 pipe 13 preferably constitutes a rotary shaft mounted in suitable bearings 21 and fixed to the upper end of this pipe or shaft is a crank

22
arm 22 by means of which the shaft, and therefore the tubular screen can be oscillated.

5 The liquid carrying in suspension the materials to be separated, enters through the ports 12 from the trough 11 and has a slow movement inwardly to the pipe 13, the rate of flow being, of course, controlled by the valve 18. This pipe and screen are caused to oscillate 10 and the rate of speed of the screen is made materially greater than the rate of flow of the liquid to the pipe. The consequence is that only fine particles of materially less area than the screen openings will pass through 15 the screen and flow out with the liquid through the pipe 15. The larger materials being baffled back, finally escape with a portion of the liquid through the outlet 17.

20 Instead of an oscillatory or reciprocatory screen, a rotary screen may be employed and would theoretically appear to be most satisfactory. Inasmuch, however, as experience has demonstrated that the particles should approach the screen at substantially right 25 angles to the screen's surface, the friction between the liquid and the screen has a tendency to cause the liquid and consequently the particles to move with the screen. With a reciprocating or oscillating screen this tendency is substantially neutralized but with a continuously rotating screen the movement of the liquid with the screen is increased. Baffles, however, may be employed to prevent the formation of currents that thus move 30 with the screen. In Figure 4, an outer cylindrical casing is shown at 23 with a cylindrical screen 24, rotatively mounted therein, the outlet for the liquid carrying the fine particles being illustrated at 25. The screen may 35 be given a continuous rotation in one direction as, for example, in the direction shown by the arrow. Interposed between the casing 23 and screen 24 are inwardly extending baffles 26 that terminate just short of the screen and thus have a tendency to prevent a circular motion of the liquid with the screen.

40 The probable action that take place will be clear by reference to Figure 5 wherein a portion of a screen is shown greatly magnified, 50 the solid elements thereof being designated 27 and the spaces between them or the screen openings being shown at 28. A large particle is shown at 29 and a smaller particle at 30. These particles move in the direction shown 55 by the arrow 31 and the screen has a movement transverse to the direction of movement of the particles as will be evident. With this structure the smaller particle 30 is shown as 60 passing through one of the openings and will proceed far enough before the adjacent bar or solid portion 27 engages it so that it will 65 pass on through the right hand side of the screen. The area of the larger particle 29 being greater and the space between the adjacent bars 27 being reduced by the movement

of the screen the chance of the particle 29 passing the screen is greatly reduced. In other words, it will be struck by one of the bars 27 and baffled back. Inasmuch as the slow movement of the liquid will carry it 70 forwardly at a low rate of speed it is almost bound to be again struck and consequently it gradually sinks to the bottom and below the screen without passing the same. It will be understood that this invention is intended primarily for fine materials and in which fine 75 mesh screens are employed. It has been found, however, that for the same work of fine screening, a coarser and therefore stronger screen can be used, due to the baffling action 80 previously described than has been possible with the ordinary methods. Also for the same reason the rate of material screened is greatly in excess of that obtained by old methods. And a further advantage results 85 in the fact that the screens are not apt to clog.

90 After careful tests, it has been found that with screens of 60 mesh having openings of about 35% of the screen area the maximum speed of a liquid approaching the screen and carrying from 20% to 50% solids is about 1.5 feet per minute. Above this rate of speed of the liquid, the screen will clog. It is of course slower for finer screens. Using a 60 mesh screen with a .0085 inch opening, the 95 percentage of -60 plus 100 mesh product passing through the screen is about 2%, thus indicating the efficiency of the machine. This efficiency is not affected appreciably by the percentage of solids in the pulp except with 100 great dilution. Nor is it affected appreciably by the rate at which the solution passes through the screen. There is, however, a little less than -60 plus 100 mesh product as the rate decreases. It is also found that the efficiency is not affected appreciably by a change 105 in the number of vibrations of the screen per minute for the same length of stroke of the screen, if within limits of 40 and 200 vibrations per minute, though the screen has more 110 of a tendency to clog with the slower rate of vibration. Indeed, it has been found that the screen will clog with a rate lower than 40 vibrations per minute where the screen is of 60 mesh and there is 35% solids in the pulp. It 115 has also been found that the efficiency is affected by any movement or agitation of the pulp on the feed side of the screen and that the less the liquid is changed from its normal course at substantially right angles to the 120 screen, the less will be the percentage of vibrations necessary per minute. In fact, a short movement of the screen has given the best results, apparently due to the fact that during the small distance which it travels the feed 125 solution or pulp approaching the screen does not have time to change its direction before the reverse movement takes place so that the liquid will not be caused to move sufficiently in the direction of the screen movement and 130

thus allow some of the coarser particles to pass through.

The following table is a result of careful tests made:—

5 *Screen cloth, 60 mesh. Rate of vibration,—constant at 150 per minute.*

Size of feed	1/2" stroke	1" stroke	3" stroke	
— 20 to — 40	7.2%	0.0%	0.0%	0.0%
— 40 to — 60	6.0	0.0	0.0	0.0
— 60 to — 100	25.6	0.5	1.4	5.8
— 100 to — 150	21.0	6.6	10.0	21.0
— 150	40.2	93.9	88.6	73.2
	100.0	100.0	100.0	100.0

15 *Density of feed, 35% solids. Density of discharge through screen, 18% solids. Rate of screening 3.76 grms. solids per sec., per sq. in. of screen cloth.*

With the same screen and conditions as in the above tests, using a one inch stroke and varying only the number of strokes per minute with a view to showing the limits of clogging, the following results were obtained:

Size of product passing through screen.

Size of feed	Strokes per min.		
	50	100	200
— 20 to — 40	7.2%	0.0%	0.0%
— 40 to — 60	6.0	0.0	0.0
— 60 to — 100	25.6	2.0	1.6
— 100 to — 150	21.0	11.5	10.8
— 150	40.2	86.5	87.6
	100.0	100.0	100.0

35 The screen clogged at about 40 strokes per minute and also operated at approximately 3.7 grms. solids per second, per square inch of screen surface, and a volume of 0.61 cubic feet per minute per square foot of screen surface.

40 A test made with a revolving screen substantially as shown in Figure 4 with baffles to lessen the circulation of the liquid outside the screen resulted in the following:—

45 *Screen cloth—60 mesh. Same sized feed as in previous tests, also 35% solids. Size of material passing through screen.*

Size of feed	Rotation speed of screen surface		
	60 R. P. M. 39 ft./min.	113 R. P. M. 89 ft./min.	200 R. P. M. 157 ft./min.
— 60	0.0%	0.0%	0.0%
— 60 to — 100	6.7	6.0	5.0
— 100 to — 150	16.0	18.0	21.0
— 150	77.3	75.4	74.0
	100.0	100.0	100.0

50 The above shows that the screened product with the use of a rotary screen is much coarser, due to the agitation of the solution adjacent to the feed side of the screen. It was also found that the capacity before the clogging point was not as high as with a vibrating screen.

From the above it seems demonstrated that three features are important:—

65 1. Rate of movement of screen surface.

2. Rate of movement of pulp liquor approaching the screen.

3. Direction of motion of pulp liquor approaching the screen.

From the foregoing it is thought that the 70 construction, operation and many advantages of the herein described invention will be apparent to those skilled in the art, without further description, and it will be understood that various changes in the size, shape, proportion and minor details of construction and operation may be resorted to without departing from the spirit or sacrificing any of the advantages of the invention.

What I claim is:—

1. The method of separating materials which consists in creating a flowing stream of said materials, causing said stream to flow through a screen at right angles to the screen, moving said screen transversely to the stream, and preventing the formation of material transverse movement of the stream adjacent to the receiving side of the screen.

2. The method of separating materials which consists in creating a flowing stream of said materials, causing said stream to flow through a screen at right angles to the screen, moving said screen transversely to the stream at a sufficiently greater rate of speed than the rate of speed of the stream to baffle back away 95 from the screen and against the stream, the coarser materials, and preventing material agitation and cross current in the stream adjacent to the receiving side of the screen.

3. In an apparatus of the character set 100 forth, a container having an inlet for a liquid having the materials to be classified in suspension therein, an outlet for the liquid and one grade of classified material, a screen movably mounted in the container between the inlet and the outlet, means for causing the liquid to flow through the screen at a predetermined rate, means for causing the screen to move through the liquid transverse to its direction of movement and at a greater rate of 105 speed than the speed of the liquid, and means adjacent to the screen for preventing cross currents in the flowing stream adjacent to the upstream side thereof.

4. In an apparatus of the character set 115 forth, a container having an inlet for a liquid having the materials to be classified in suspension therein, an outlet for the liquid and one grade of classified material, a screen movably mounted in the container between the inlet and the outlet, means for causing the liquid to flow through the screen at a predetermined rate, means for vibrating the screen through the liquid transversely of its direction of flow and at a speed greater than the speed of the liquid, and baffles on the upstream side of the screen and adjacent thereto for preventing material currents crosswise to the stream and longitudinally of its direction of movement.

5. In an apparatus of the character set forth, a container, a substantially cylindrical screen in the container, means for supplying a fluid with the materials to be classified therein, to the container on one side of the screen, means for carrying off the fluid from the other side of the screen, means for controlling the rate of flow of the fluid through the container, means for rotating the screen, and baffles mounted in the container on the upstream side of the screen and directly adjacent thereto to prevent the creation of cross currents at the screen that would otherwise be created thereby.
- 10 6. The method of separating materials which consists in creating a quietly flowing stream of said materials, causing said stream to flow through a screen placed across the same, and moving said screen transversely to the stream at a speed sufficiently greater than 20 the speed of the stream to cause the coarser materials to be struck and baffled back away from the screen against the flowing screen, the screen being thereby kept substantially unobstructed by its own action in 25 the stream, and maintaining a constant and substantially undisturbed flow of the stream adjacent to and through the screen.

In testimony whereof, I affix my signature.

LOUIS S. DEITZ, JR.
